**STITCHING AND SEAM GUIDE FOR
SEWING MACHINES**Dorothy Y. Kirby, Rte. 2, Box 97,
Clermont, Fla. 32711Filed Aug. 19, 1966, Ser. No. 573,652
4 Claims. (Cl. 112—153)**ABSTRACT OF THE DISCLOSURE**

A stitching and seam guide for sewing machines made from a flat metal plate approximately $\frac{3}{32}$ inch thick with edges formed to guide material being sewed in a direction to form an even seam. One relatively long straight edge guides material when sewing a straight seam; a relatively short straight edge joining the relatively long straight edge guides material when sewing a narrow seam. Near one end of the guide, at one side, is a convexly curved edge for guiding material when sewing a curved seam. On the side of the plate opposite the convexly curved edge is a relatively short straight edge and a concavely curved edge joins the last mentioned straight edge at a sharp angle to the first mentioned relatively long straight edge to provide a point for guiding material when sewing a seam with sharp angles or when sewing seams of varying directions.

This invention relates to a seam or stitching guide as an attachment for a sewing machine and has for an object to provide a unitary guide which shall be adapted for various stitching operations in the fabrication of a garment.

Particular objects of my invention are to provide a line of stitching in a garment an even distance from the cut edge of a seam; a line of top-stitching an even distance from a finished edge of a garment; also a line of top-stitching an even distance from the main line of stitching of a welt seam, or zipper.

Briefly, my improved seam and stitching guide comprises a unitary or integral flat plate, having a relatively long straight edge on one part, a convexly curved edge on another part, a relatively short straight edge which can be used in front of or near the toe of the presser foot of a machine for use in top-stitching a narrow edge such as the edge of a belt or the finished edge of a collar or front of a blouse. It also includes a pointed portion for use in top-stitching an even distance from the finished edge of scallops. The advantage of the flat guide is that it can be used under the fabric as a guide to insure a straight stitching when top-stitching a welt seam or top-stitching a zipper to the fabric. The seam or stitching guide is secured to the bed plate of the machine by means of a set-screw and can be turned to various positions to present selected edges of the guide opposite the machine needle. Being flat and reversible it may be readily positioned for the intended use.

These and other features of my invention are illustrated in the accompanying drawings, forming a part of this application in which—

FIG. 1 is a plan view of the guide;

FIG. 2 is an edge view of the guide;

FIG. 3 is a plan view showing the guide mounted on the bed plate of the machine in position for stitching a straight seam;

FIG. 4 is a similar view showing the guide mounted on the bed plate of the machine in position to guide the fabric in stitching an inside curved seam or top-stitching the finished edge of an inside curve;

FIG. 5 is a plan view showing the guide mounted in position for top-stitching along a narrow edge of a belt or other part of a garment;

2

FIG. 6 is a plan view showing the guide mounted in position, and the method of utilizing it, in stitching a welt seam;

FIG. 7 is a plan view showing the guide mounted in position for top-stitching around scallops in a garment; and

FIG. 8 is a perspective view showing the guide mounted in position on a sewing machine but with no material or fabric being shown.

Referring to the drawings for a better understanding of my invention my improved stitching guide comprises a unitary, integral flat plate having a relatively long straight edge 10, which can be employed, as hereinafter described, for stitching the straight seam of a garment. At the opposite end of the guide from the straight edge 10 is a convexly curved edge 11 for guiding fabric when stitching inside curved seams as found around the neck and armholes of a garment. At edge 12 I provide a relatively short straight edge on the guide which is used in front of the short toe of the presser foot as in guiding the fabric when top-stitching a very narrow edge, and when stitching along edges of a belt or along the outside edge of a collar or front of a blouse. At 13 I provide a pointed portion which is employed when top-stitching around the finished scalloped edges of a garment. A straight edge 15 along the edge of the plate opposite the convex edge 11 extends in a direction normal to the long straight edge 10 and is somewhat shorter than said long edge. Extending between the straight edge 15 and the pointed portion 13 is a concavely curved edge 17. The edges 15 and 17 further assist in sewing seams having sharp turns and of varying lengths and directions. The guide is secured to the bed plate of a sewing machine by means of a set-screw 14 which passes through an elongated slot 16 and into a hole provided in the bed plate of the sewing machine, all sewing machines with which I am familiar are provided with such holes for securing attachments to the machine. My improved guide being formed from a flat plate, it may be used under the fabric as well as at the edge of the fabric.

In FIGURE 3 of the drawings I show my improved stitching guide mounted at a position wherein the straight, or relatively long, straight edge 10 is opposite the needle 21 and is parallel to the presser foot 18. The fabric, indicated at 19, is fed through the machine with the outer edge bearing against the relatively long straight edge 10 of the guide. It will be understood that the guide may be set toward or away from the needle 21 as indicated by the arrows to determine the desired width of the seam. In feeding the fabric through the machine, while stitching any of the seams or edges shown in the drawings, the sewer holds her finger on the fabric in front of the guide to be sure that the edge of the fabric bears against the edge of the guide.

FIGURE 4 illustrates the seam or stitching guide mounted in position with the curved edge 11 opposite the presser foot 18 and the needle 21 of the machine, and the sewer guides the material with the outer edge bearing against the edge 11 of the seam guide. In this way, an even-width curved seam is stitched.

In FIGURE 5 of the drawing I show my improved seam guide placed, as indicated, at a position wherein the relatively short straight edge 12 is in front of the short toe of the presser foot so it can be used as a guide in top-stitching a very narrow edge as with a belt, indicated at 23.

In FIGURE 6 of the drawing I show my improved seam guide in position for top-stitching a welt seam. As is well understood, in sewing a welt seam, two pieces of fabric are joined together in a main seam, indicated at 24, with the edges turned under as indicated at 26. The edges 26 are then stitched to the outside of the

fabric as indicated at 27. In feeding the material through the machine, the finger of the sewer, indicated at 28, feeds the material with the edge of the folded-over fabric seam 24 bearing against straight edge 10 of the guide. In this way I provide means for top-stitching a straight, even, 5 welt seam on a garment.

In FIGURE 7 I show my improved stitching guide mounted in position for top-stitching around the scalloped edges 29 of a garment or piece of fabric. In this position, the pointed portion 13 of the guide is turned opposite the needle 21 and is secured in position. The finished scallops of the fabric 29 are fed around this pointed portion so as to provide an even stitching. The pointed portion of the guide enables the sewer to turn the fabric around the point. 10

In FIGURE 8 of the drawing I show a portion of a machine 31 with the presser foot 18 and with feed mechanism indicated at 32, and the needle 21. My improved guide is shown mounted on the bed plate 33 of the machine by means of the set screw 14. The particular form of the presser foot and feed mechanism form no part of my present invention and are shown for purposes of illustration only. Various other forms known to those skilled in the art may be employed. 15

While my improved seam and stitching guide may vary somewhat in thickness, it should be of a thickness such that the fabric being stitched will not jump or slide over the top of the guide and in which the edge of the guide may be readily felt by the finger of the sewer through the fabric being stitched. At the same time, it should not be so thick as to constitute a drag on the fabric. In actual practice I have found that a thickness of approximately $\frac{3}{32}$ of an inch is satisfactory. 20

From the foregoing it will be apparent that I have devised an improved seam or stitching guide which is 35 simple of construction and which may be easily mounted on a sewing machine and set to the proper positions for even stitching of seams and for top-stitching the various finished edges of a garment.

As many apparently widely different embodiments of this invention may be made without departing from the spirit and scope thereof, it is to be understood that the invention is not limited to the specific embodiments thereof except as defined in the appended claims. 40

What I claim is:

1. A seam guide for sewing machines comprising
  - (a) a unitary flat plate,
  - (b) a relatively long straight edge at one end of the plate for guiding material when sewing a wide straight seam,
  - (c) a relatively short straight edge joining said relatively long straight edge at an angle thereto for guiding material when sewing a narrow seam,
  - (d) a convexly curved edge at one side of the plate near the end opposite the relatively long straight edge for guiding material when sewing a curved seam,
  - (e) a straight edge on the opposite side of the plate extending in a direction normal to the relatively long straight edge,
  - (f) a concavely curved edge of the plate joining said last mentioned straight edge and said relatively long straight edge and terminating at an angle to provide a sharp point for guiding material when sewing a seam with sharp angles,
  - (g) and means to secure the seam guide on a sewing machine to place said edges selectively in guiding position.
2. A seam or stitching guide as defined in claim 1 in which the means for securing the guide to the sewing machine comprises an elongated slot provided in the guide and a set screw passing through the slot and adapted to be secured to the machine.
3. A seam guide as defined in claim 1 having a uniform thickness of approximately $\frac{3}{32}$ inch.
4. A seam guide as defined in claim 1 which is reversible and may be employed with either side up.
